UNITED STATES PATENT OFFICE.

BOSE B. BOWERS, OF MACON, GEORGIA.

CAR-DOOR FASTENING.

No. 880,621.

Specification of Letters Patent.

Patented March 3, 1908.

Application filed June 4, 1906. Serial No. 320,186.

To all to whom it may concern:

Be it known that I, BOSE B. BOWERS, a citizen of the United States, residing at Macon in the county of Bibb and State of Georgia, have invented certain new and useful Improvements in Car-Door Fastenings; and I do hereby declare the following to be a full, clear, and exact description of the invention, such as will enable others skilled in the art to which it appertains to make and use the same.

The latch forming the subject-matter of this invention is intended to provide a strong, practicable and simple fastening for sliding doors, more particularly for the sliding doors of freight and express cars; and also to afford a convenient means for locking or sealing the door when latched.

The improvement pertains to latches of that type wherein a hasp or latch-bolt carried by the sliding door is engaged by a vertically sliding gravity actuated keeper-bolt on the door-jamb when the door is shoved to or closed.

In the accompanying drawings, which form a part of this specification, Figure 1 is a front view of a latch embodying my invention, showing its parts or members respectively attached to fragments of a car-door and adjacent jamb of the door-opening, the door being represented partially open or separated from the jamb, so that the latch appears unfastened, with its members out of engagement. Fig. 2 is a similar view in which the car-door is represented closed or shoved against the jamb, so that the latch appears fastened. Fig. 3 is a side view of the member attached to the door-jamb, together with the sliding keeper-bolt therein. Fig. 4 is a central horizontal section through the latch, when in fastened position, said section being taken on line 4-4 of Fig. 2. Fig. 5 is a detail perspective of the gravity actuated keeper-bolt. Fig. 6 is a detail view of the member attached to the door-jamb, and which provides a casing or guide-way for the keeper-bolt.

1 indicates a fragment of the sliding car-door, and 2 denotes the adjacent portion of the door-jamb against which the door abuts when shoved to or closed, the outer sides of the door and jamb being substantially flush, as usual in car-door constructions.

The latch comprises only three simple parts, which may be described as follows: On the front face of the door is attached by

screws or bolts a metal base-plate 3, which is formed or constructed with a rigid latch-bolt 4, offset from the back of said plate as indicated in Fig. 4, and having a projecting substantially spear-shaped pointed head 5, a slot or recess 6 being cut in the upper edge of the latch-bolt to form an engaging shoulder at the rear of the head. Similarly attached to the side of the door-jamb is a companion plate 7, having on its face two parallel outstanding vertical flanges 8 with an intermediate slide-way 9, constituting the casing for the sliding gravity-bolt 10, and having also a narrow transverse opening or slot 11 extending through said flanges 8 to receive the head 5 of the latch-bolt 4. The mouth 12 of said opening 11, where the end of the latch-bolt or rigid hasp enters, is flaring or enlarged, being inwardly beveled all around, as shown in Figs. 3, 4 and 6, the object of which is of course to guide the latch-bolt into the slot when the car-door may have become more or less out of line, as is frequently the case in usage. The third member of the latch is the said gravity-actuated-keeper bolt 10, which is a short, straight bar slidably secured in its vertical guide-way 9 by means of two transverse pins 13 inserted through openings in the flanges 8 and through longitudinal slots 14 in the keeper-bolt, which is thus free to move up and down between the limits allowed by its pin and slot connections. Said keeper-bolt 10 has at its lower end an outwardly projecting finger-hold 15 for raising or lifting it. When released, the keeper-bolt will automatically drop back to its lower position by gravity. In the rear edge of said keeper-bolt is a rectangular notch 16 whose upper end provides an overhanging ledge or shoulder 17 that occupies or projects across the upper half of the transverse slot 11 when said keeper-bolt is down; but when said keeper-bolt is raised its said notch 16 is substantially co-incident with the transverse slot 11. On closing or shoving to the sliding door, the head 5 of the rigid latch-bolt 4 enters the widened mouth 12 of the slot 11 and its inclined edge rides under the beveled ledge 17 of the keeper-bolt 10 which is automatically raised thereby until the recess 6 in the upper edge of the latch-bolt comes in line with the vertical guide-slot 9, whereupon the keeper-bolt drops by gravity and its shoulder 17 enters and engages with the shoulder formed by said notch 6 of the latch-bolt, thus securely latching the door.

To unlatch, it is merely necessary to lift the keeper-bolt by its finger-hold 15, thus freeing the latch-bolt and allowing the car-door to be slid open.

- 5 To receive either a lock or seal, the flanges 8 and intermediate keeper-bolt 10 are provided with transverse holes 18, preferably in the lower parts of said flanges and keeper-bolt, which holes register when the keeper-bolt is down. Hence, after the door is latched, a padlock may be secured through said holes, or the latch can be sealed by means of a sealing-wire or metal strip inserted through said holes, so that it would be impossible to unlatch and open the door without first removing the lock or seal.
- 10
- 15

The advantage of this device over many similar contrivances hitherto devised lies in its simplicity and nice construction, and its 20 practicability as a strong and efficient fastener for sliding car-doors.

Having thus fully described my invention, what I claim as new and desire to secure by Letters Patent of the United States is:—

- 25 In a sliding-door latch, the combination of a base-plate having a pair of spaced out-

standing flanges disposed to form a vertical guide-way, said flanges being provided with opposed transverse perforations together forming a keeper-opening intersecting said 30 guide-way, a gravity-actuated keeper-bolt slidably secured in the guide-way and formed to provide between its ends an engaging shoulder normally traversing the keeper-opening, and a companion base-plate having 35 a rigid latch-bolt provided with a pointed substantially spear-shaped head terminating at its rear in an engaging shoulder, said head being designed to pass through the keeper-opening and having an inclined edge disposed 40 to ride beneath the shoulder of and automatically lift the keeper-bolt, and the latter being adapted after passage of the head to descend automatically by gravity for effecting interlocking of said engaging shoulders. 45

In testimony whereof I affix my signature, in presence of two witnesses.

BOSE B. BOWERS.
